Primary Examiner—Elizabeth A. Albert*(74) Attorney, Agent, or Firm*—The Webb Law Firm(57) **CLAIM**

The ornamental design for a desk organizing container, as shown and described.

DESCRIPTION

FIG. 1 is a front view of the desk organizing container of the invention;

FIG. 2 is a cross-sectional view taken along the lines II—II of FIG. 3;

FIG. 3 is a bottom plan view thereof;

FIG. 4 is a top plan view thereof;

FIG. 5 is a front view of the desk organizing container in accordance with an alternate embodiment of the invention;

FIG. 6 is a cross-sectional view of the alternate embodiment taken along the lines VI—VI of FIG. 7;

FIG. 7 is a bottom plan view of the alternate embodiment; and,

FIG. 8 is a top plan view of the alternate embodiment.
